UNITED STATES PATENT OFFICE.

ARTHUR PAULSON, OF NEW YORK, N. Y.

DESIGN FOR A LETTER-FILE.

59,508.

Specification for Design.

Patented Oct. 25, 1921.

Application filed February 12, 1921. Serial No. 444,609. Term of patent 14 years.

To all whom it may concern:

Be it known that I, ARTHUR PAULSON, a citizen of the United States, residing at New York city, in the county of New York and State of New York, have invented a new, original, and ornamental Design for a Letter-File, of which the following is a specification, reference being had to the accompanying drawing, forming a part thereof.

The drawing is a perspective view of a "letter file" showing my new design.

I claim:

The ornamental design for a letter file as shown.

ARTHUR PAULSON.
